HYDRAULIC SYNCHRONIZED LIFTING MEANS FOR SLIPS

Filed Oct. 21, 1929

Inventor

JAMES S. TAYLOR.

By

Tom J. Bowman. Attorney

UNITED STATES PATENT OFFICE

JAMES S. TAYLOR, OF TULSA, OKLAHOMA

HYDRAULIC SYNCHRONIZED LIFTING MEANS FOR SLIPS

Application filed October 21, 1929. Serial No. 401,322.

This invention relates or pertains to a lifting device and more particularly to a hydraulic synchronized slip actuating apparatus which is adapted to be entirely contained on and within the bowl or base which houses the slip blocks or 'slips'.

Present day devices and arrangements for lifting the wedge shaped slip blocks from their seated or gripping position are very cumbersome due to the fact that leverage systems are used to obtain the necessary force to do so and consequently take up much valuable space. This space is very desirable, if not absolutely necessary, during certain operations, such as a cementing job, as will be readily understood by those skilled in this art. Moreover, such mechanical systems tend to raise the center of gravity of the unit and render it less stable.

It might be noted at this point that my construction is adaptable to a wide number of different installations. For example, it may be expediently applied to a rotary table, a spider or an elevator.

One main object of my device is to do away with any system of levers or the like over or around the casing. I do this by my novel hydraulic means, and, to the best of my knowledge, I am the first to inventively create a manually operated hydraulic system of this type.

Another object of my invention is to provide a construction which will have a low center of gravity and which will also be balanced about its vertical axis so that when it is applied to an elevator it will tend to stabilize the same rather than cause it to be unsteady when in suspended position. In this regard it might be mentioned that there are no protruding levers or parts which might cause injury to the workmen. Also, means are provided to retain the slips in position even though the bowl or base containing them should be inverted.

Another object is to apply the force which lifts the slip blocks in a direction which is in parallelism to their direction of movement. This reduces the force required to lift the blocks to a minimum.

Yet another object is to provide means for

aiding the operator in pulling down the lever whereby the fluid system is placed under pressure. Hand in hand with this object it is to be noted that I have further means which releases the fluid system from pressure when such is desirable. For example, as will be fully understood from reading the detailed description following, when the cammed lever is in its lower position the slip blocks are elevated and the fluid is under pressure. Now, if the lever is suddenly lifted to about a horizontal plane only the spring will tend to hold the slips from sliding downwardly to an engaging position. Since the spring is not strong enough to support the weight of the slips it will be compressed and the slips will slide downwardly due to gravity. However, in order to add snap to the action of the slips, I provide another cam on the lever which releases the spring tension entirely.

A still further object of my invention is to provide a simple, cheap and effective hydraulic well casing gripping device which can be readily adapted to perform its several functions with efficiency and dispatch.

For the purpose of illustrating the invention, I have shown in the accompanying drawings a typical embodiment of it, which, in practice, will give reliable and satisfactory results. It is, however, to be understood that this embodiment is typical only and that the various instrumentalities of which my invention consists can be variously arranged and organized, and that the invention is not limited to the precise arrangement and organization of these instrumentalities as herein set forth.

In the accompanying drawings;

Figure 1 is a top or plan view of a bowl or base with slips equipped with my novel lifting arrangement.

Figure 2 is an enlarged broken sectional view taken along either of the lines 2-2 of Figure 1.

Figure 3 is a view in cross section taken along the line 3-3 of Figure 2.

Figure 4 is a schematic illustration of my double cam.

Figure 5 is a diagrammatic showing of the

ducts in the base. This view is in plan, similar to Figure 1.

Figure 6 is a top view of the handle.

Figure 7 is an enlarged view of the plunger operating means.

Similar numerals refer to similar parts throughout the several views.

In the practice of pulling or inserting casings in a well it is customary to have a casing holding means adapted to be set upon the floor of the rig and also have a similar gripping or holding device adapted to be supported in movable relationship thereto.

In my improved device —10— designates the base or bowl of a casing holding means which may be supported as desired. A tapered hole —11— is formed therein and slips or slip blocks —12—, —13—, —14—, and —15— slide therein in the usual manner. These blocks are interlocked as at —16— and hence must move as a unit. Blocks —12— and —14— have ears —17— and —18—, respectively, and are identical in other respects. Blocks —13— and —15— are also similar in construction.

As all of the slip blocks are keyed to the walls of the tapered hole —11— in exactly the same manner only one will be set forth in detail. Referring to Figure 3, —20— designates a spline or key which rides in the undercut slot or keyway —21— and hence causes the slip block to move outwardly as it travels upwardly.

Referring now to Figures 2 and 5 it will be noted that a passageway or duct is formed in the base element. This duct might consist of a pipe. This is indicated by the character —23— and egresses in three places. Small bores, —24— and —25—, parallel to the splines —20—, are joined to the duct near each end thereof and a larger cylinder or bore —30— is connected therebetween. Hence a continuous chamber is formed and such is filled with a liquid —29—.

Bores —24— and —25— have identical structure therein and hence only that shown in bore —24— will be recited. A plunger —26— slides up and down as acted upon by opposing forces, and packing —27— held therearound by the stuffing box —28— prevents the escape of the entrapped fluid. Suitable stops —31—, fastened to the base —10— as at —32—, prevents excessive upward movement of the slip blocks.

A piston or plunger —33— reciprocates in the bore or cylinder —30— and as this piston moves downwardly the other two plungers must necessarily move upwardly. And, since the plunger —33— has a cross sectional area of more than the sum of the areas of the other two plungers it stands to reason that their velocities will be greater. This is very desirable as it makes for snappy action and quick gripping. Packing —34—, held

tightly in place by the stuffing box —35— prevents leakage of the oil or the like past the plunger.

The piston —33— is threaded at its upper end as at —36— and the unit —37— is adjustably screwed thereto as at —38—. This unit —37— consists of a stem —39— having a shoulder —40— and a base portion —41— having depressed surfaces —42— and —43—. A bifurcated handle —50—, having cams —51— and —52— thereon, see Figure 6, is pivoted to the uprights or lugs or brackets —60— and —61— as at —62— and —63— respectively.

The cams, —51— and —52—, are adapted to engage in the depressed surfaces —42— and —43—, respectively, and prevent any turning of the unit —37—. However, the real function of the cam surfaces which contact with the base or plate portion —41— is to cause it to move downwardly as the handle —50— is pulled downwardly.

Referring to Figure 4, —L— designates that portion of each cam which acts against the plate —41— and causes it to be forced downwardly a distance indicated by the letter —P—. It will be noted that the handle may be moved through an arc as shown by the letter —R— but only the movement during part of the entire movement —R— is utilized in forcing the plunger —33— downwardly.

A bell crank or lever —70—, pivoted to the bracket —61— as at —71—, is adapted to be swung above the plunger to hold it in its bottommost position when such is desired. Cam —90—, on the lever —50—, see Figs. 6 and 7, is so positioned thereon as to trip the bell crank —70— just before the lever —50— reaches its top position.

A disc —80— is slidably mounted on the upper part of the stem —39— and a spring —81— set thereon. A casting —82— rides against the upper ends of these springs and may be forced downwardly by means of the bolt and locknut arrangement —83— threadededly inserted through the upper part of the bracket —61—.

Referring again to Figure 4, —U— designates that arc of the cams which contact with the bottom side of the disc —80—. This contact occurs only when the handle —50— is near its upper end of its stroke. In other words, the cam portion —L— does not function when the upper cam is functioning. The short cammed portion —H—, is merely adapted to hold the handle in its upper position.

The operation is readily understood. When the device is standing idle the handle is in its top position and remains so by virtue of the spring force of spring —81— acting on the reverse cam surface —H—. The handle may be constructed so as to operate in any chosen plane. The springs, at this time, are merely pushing against the brackets —61—.

—60— and —61— through the medium of ble cam thereon adapted to ride against the pivot points —62— and —63— and the two parallel depressed faces cams —51— and —52—.

When or after the handle is pulled or rotated downwardly through an arc equal to $U + H$ the disc —80— seats on the shoulder —40— and thereafter the spring pressure pushes against the stem —39— and consequently the plunger —33—. Next, further rotation of the handle causes the cammed portion —L— to operate on the plate —41— and this force is added to the spring force in causing the movement of the plunger. It will be noted that the springs are under considerable pressure and that when the handle is operated quickly the spring force will act in the manner of a blow and this impact together with the operator's force on the handle will cause an upward movement of the plungers under the slips in such a sudden and powerful fashion as to preclude any sticking or binding thereof.

After the slips are raised lever —70— may be operated to bring its lower end above the plate —41— thus holding or locking the slips in their upper position. The handle or lever may now be moved to substantially its top position and then when it is desired to release the fluid pressure thereby lowering the slips, the operator may either trip the lever —70— by directly pulling the same or else he may indirectly trip it by moving the lever —50— slightly upwardly thus causing the lug or cam —90— to wedge the bottom of the lever —70— from its seat on the plate —41—.

While I have described a complete embodiment of my invention I do not wish to be limited to the particular construction shown, my invention being in fact limited solely by the attached claims.

What I claim is:

1. A hydraulic synchronized lifting apparatus comprising a horizontal base having a substantially vertical hole therethrough, slips having ears near their tops adapted to slide against the walls of the hole, said base having bores under the ears of the slips and parallel to the walls of the hole, a passageway interconnecting all of the bores, a liquid or fluid in the passageway, plungers in the bores, said plungers being adapted to be reciprocated and of such length as to engage with the ears of the slips and lift said slips, and means for placing the liquid or fluid under pressure.

2. An apparatus as set forth in claim 1 but further characterized by the fact that the means recited therein consists of a bore or cylinder interconnected to the passageway, a piston having a threaded upper end mounted in the bore or cylinder, a plate having two parallel depressed surfaces in its upper face and a threaded hole in its lower face adapted to be adjustably connected to the upper end of the piston, and lever means having a dou-

ble downwardly convergent tapered aperture therein, slip blocks adapted to engage the sides of said aperture to clamp the well ease shoulder —40— and the like, said base having a passageway therethrough opening near each of the slip blocks, plungers snugly fitting in said openings and in such a position as to exert lifting force on the slip blocks when moved in one direction, said plunger movement being parallel to the slip block's movement, liquid in said passageway and means to exert pressure on the liquid whereby lifting force is exerted on the slip blocks.

4. A device of the character described consisting of a bowl having a tapered hole therethrough, two slips therein, said bowl having a passageway therethrough which egresses near the slips, plungers reciprocably mounted near either end of the passageway and adapted to directly engage with the slips, fluid in the passageway, and means to place the fluid under pressure whereby the plungers will push against the slips.

5. A device of the character described consisting of a bowl having a tapered hole therethrough, two slips therein, said bowl having a passageway therethrough which egresses near the slips, and means slidably mounted in the passageway near each end of the passageway and contacting with the slips, said passageway being adapted to receive a liquid and means for forcing the liquid along the passageway.

6. In a well pipe clamping device having a base, hydraulically operated slips therein and means operated by pressure fluid for operating said slips, the combination of means for furnishing pressure fluid to actuate the slips, said means comprising a piston, said base having a bore to receive said piston, said piston snugly and slidably fitting said bore and adapted for reciprocation therein, a base portion rigid with the piston, a stem having a shoulder thereon extending from said base portion, a disc mounted on the shoulder, spring means acting on the disc, and cam means placed between and cooperatively associated with the base portion and the disc.

7. A well pipe clamping device having a base, hydraulically actuated slips therein and means operated by pressure fluid for operating said slips, means for operating the slips comprising a hydraulic system having fluid therein in a chamber, and a bore connecting to said chamber, a piston snugly and slidably fitting in said bore, spring means abutting against the piston to push the piston into its bore and auxiliary means, including a lever and means actuated by the lever riding against the piston, whereby the piston is pushed into its bore.

8. A hydraulic lifting device of the character described comprising a base having a tapering bore therethrough, a number of gripping devices movable in said bore, hydraulic elevating mechanism for said gripping devices, and spring means for maintaining the fluid in the mechanism under pressure.

In testimony whereof I affix my signature.
JAMES S. TAYLOR.
